JOURNAL LUBRICATOR

Llewellyn E. Hoyer, Wyckoff, and Edward R. Goryca, Mahwah, N.J., assignors to American Brake Shoe Company, New York, N.Y., a corporation of Delaware

Filed Dec. 1, 1958, Ser. No. 777,485

7 Claims. (Cl. 308—88)

This invention relates to a lubricator for lubricating a journal disposed for rotation in a journal box.

The present invention relates to a lubricator that is adapted to transmit lubrication in the bottom of a railroad journal box on to the journal portion of the car axle disposed in the journal box, and thus the present invention has its primary utility in connection with otherwise standard railroad journal box equipment wherein the journal of the car axle rotates on a so-called partial bearing mounted within the journal box.

The long-practiced method of lubricating the journal and the journal bearing of a railroad car axle has been by means of waste packing packed in the bottom of the journal box in contact with the lower periphery of the journal. It is generally now considered, however, that waste packing is one of the primary causes of hot boxes, and as a consequence efforts are being taken to supplant waste packing by a more satisfactory form of lubricating means.

It will be recognized that a lubricator for a railroad car journal should be relatively simple in construction, not so much because of cost considerations as the greater likelihood of failure of a lubricator that depends upon relatively complicated structure. Moreover, with a lubricator embodying many parts there is a greater likelihood of a loose or weakened part becoming entrained on the journal, and of course if this occurs a severe accident will most likely be caused either by journal or bearing failure.

In view of the foregoing, the objects of the present invention are: to construct a lubricator for the journal of a railroad car including a resilient base member capable of conforming to the shape of the bottom of the journal box, a pair of arms flexibly connected to the base member and projecting upwardly therefrom and supporting a readily renewable wick, and spring means acting between the base member and the arms to urge the arms inwardly toward one another to contact opposite sides of the journal; to embody in a lubricator of the foregoing kind retainers cooperating with rigid parts in the journal box to prevent relative displacement of the lubricator; to so support the wick as to relay lubricant from the supply in the bottom of the journal box to the journal with a high degree of efficiency; and to construct a journal lubricator with relatively few working parts with consequent minimum failure possibility.

It is important that a lubricator for a railroad car journal be capable of sustained contact with the car journal and effective operation even at times when the supply of lubricant is tending toward a minimum; and the attainment of these ends constitute another object of the present invention. Other objects of the present invention are to construct a lubricator for the journal of a railroad car consisting almost entirely of flexible non-metallic parts, whereby the same will readily conform geometrically to variant conditions and will not wear the journal, and to so dimension the various parts thereof as to prevent shifting of the lubricator and prevent any significant

contact of the wick part of the lubricator with portions of the journal which might become fouled thereon.

Other and further objects of the present invention will be apparent from the following description and claims and are illustrated in the accompanying drawings which, by way of illustration, show preferred embodiments of the present invention, the principles thereof and what we now consider to be the best mode contemplated for applying these principles. Other embodiments of the invention embodying the same or equivalent principle may be used and structural changes may be made as desired by those skilled in the art without departing from the present invention and the purview of the appended claims.

In the drawings:

Fig. 1 is a section through a standard railroad journal box and associated parts showing a lubricator of the present invention installed in operative position therein;

Fig. 2 is a partial end elevation of the Fig. 1 lubricator;

Fig. 3 is a section on line 3—3 of Fig. 2;

Fig. 4 is a top plan view of the Fig. 1 lubricator;

Fig. 5 is a section on line 5—5 of Fig. 4;

Fig. 6 is a plan view showing the form of the retainers;

Fig. 7 is a plan view of a modified construction;

Fig. 8 is a view on the line 8—8 of Fig. 7;

Fig. 9 is a partial sectional view similar to Fig. 1 illustrating the Fig. 7 lubricator as installed;

Fig. 10 is a plan view of still another modified form of the invention;

Fig. 11 is an elevation, partly in section, of the lubricator shown in Fig. 10; and

Fig. 12 is a view on the line 12—12 of Fig. 11.

In Fig. 1 of the drawings, there is illustrated a journal box JB of standard or AAR approved cast construction.

The journal box JB includes spaced apart opposed side walls SW, a rounded bottom wall BW joining the lower edges of the side walls SW, and a top wall TW. As is well known, the journal J of the railroad car is extended into the cavity of the journal box defined by the walls thereof, and it should be pointed out that the section in Fig. 1 is at the outer end of the journal box, that is, the end away from the car axle. The journal J rotates on the bearing lining BL of a partial bearing B which is retained in place by a conventional wedge W having a lower surface complementary to the angled back of the bearing B, the wedge W being wedged in place between the top wall of the journal box and the back of the bearing.

The respective side walls of the journal box are formed with inwardly directed so-called stop columns SC-1 and SC-2, and the bearing B is provided adjacent the forward end thereof with lugs L which are engageable with the front walls of the respective stop columns serving to limit displacement of the bearing B. As will be explained, the stop columns SC-1 and SC-2 are utilized under the present invention to maintain the lubricator of the present invention in place.

Disposed below the stop columns and projecting inwardly from the opposed side walls SW of the journal box are so-called waste retainer ledges WL-1 and WL-2. These ledges are present in most standard journal boxes

for the purpose of retaining the waste packing, where used, in place, and under the present invention the waste ledges can also be used to limit displacement of the lubricator of the present invention as will be explained.

The bottom of a standard journal box as JB is adapted to serve as a reservoir for lubricating oil having a depth of several inches. The long-practiced prior method was to pack cotton waste in the cavity of the journal box below the journal, the waste serving to relay lubricant to the journal by capillary action. As has been explained above, this method of lubrication is considered to be a constant source of the hot box problem, and under the

present invention is eliminated by having resort to a lubricator 20, Figs. 2 to 6, which is adapted to transmit lubricant to the journal by means of a woven wick thereby eliminating the objection to the loose strand nature of waste packing.

The lubricator 20 embodies a base member 21 of resilient oil-resistant hard rubber Durometer hardness approximately 70-90, capable of conforming to the configuration of the bottom wall of the journal box as best shown in Fig. 1 of the drawing. Thus, the base member 21 is of flat rectangular configuration in its collapsed or unmounted state as shown in Figs. 4 and 5 and includes parallel elongated edges 22 and 23 and parallel transverse edges 24 and 25. The transverse edges 24 and 25 correspond to the side walls SW of the journal box, which is to say that the edges 24 and 25 will extend parallel to the side walls of the journal box when the lubricator 20 is mounted therein, and in such circumstances the longitudinal edges 22 and 23 are of course respectively at the front and rear ends of the journal box. As will be appreciated from the description to follow, however, the lubricator 20 is fully reversible in the sense that it is immaterial which longitudinal edge 22 or 23 becomes the leading edge at the time the lubricator is inserted in the journal box, and this of course represents an important attribute of the lubricator of the present invention.

Oil in the bottom of the journal box is to be relayed to the journal by a wick, and to this end a pair of arms 30 and 31 are molded integrally with the base member 21 whereby the arms 30 and 31 are of resilient hard rubber and thereby joined flexibly to the base member at the juncture of the arms and the base member. Thus, the arms 30 and 31 are located in spaced vertically projecting relation at the medial portion of the base member 21, and the arrangement is such that the left and right hand sections 21A and 21B of the base member outwardly of the arms 30 and 31, respectively, are of equal extent whereby the lubricator is perfectly symmetrical both in a longitudinal and transverse sense. The arm members, as best shown in Fig. 4, extend for the full lateral or transverse dimension of the base member 21, and this dimension corresponds approximately to the length of the journal between the collar, not shown, at the outer or free end thereof and the first annular fillet, not shown, adjacent the dust guard diameter of the journal. In other words, the arms 30 and 31 correspond approximately in length to the axial dimension of the journal J that rotates on the bearing B, and as will be explained this construction enables lubricant to be relayed uniformly by the action of a wick to the journal substantially for the entire axial bearing extent thereof.

The arms 30 and 31 are inherently flexible as a result of being molded integrally with the base member 21, and the space dimension between the arms 30 and 31 is such that when the lubricator is installed in position below the journal the arms 30 and 31 are spread apart by the journal as will be apparent from a contrast of Fig. 5 and Fig. 1 of the drawing. Such spreading of the arms 30 and 31 assures a firm contact between the journal and the wick to be described which is supported by the arms 30 and 31, but in order that this will be a positive action, that is, a positive clasp, spring means are provided which act between the respective arms 30 and 31 and the base member 21. Such spring means in the present instance take the form of a pair of webs 35 and 36, normally of generally arcuate form, which extend from the outer sides of the arms 30 and 31 substantially at the transverse mid lines thereof to juncture lines on the base member 21 outwardly of the juncture lines joining the arms 30 and 31 to the base member 21. As a consequence of this, when the lubricator is mounted in operative position in the journal box as shown in Fig. 1, the webs 35 and 36 assume an accordian or bellows condition due to the spreading apart of the arms 30 and 31 during installation of the lubricator. Thus, when the lubricator is installed in position, the webs 35 and 36 tend to be shortened,

manifest in generally V-shaped bulges 37 and 38, Fig. 1. In other words, at the time of installation, the webs 35 and 36 are compressed whereby a spring action is originated tending to hold the arms 30 and 31 inwardly against the journal with a relatively strong force.

The arms 30 and 31 serve primarily as a support for a wick 40, Figs. 1, 2 and 3, in the form of a woven tube of the kind disclosed in application Serial No. 582,030, filed May 1, 1956, now Patent No. 2,939,751, issued June 7, 1960. Thus, the tube 40 is of one-piece, sleeve-type construction having open ends, and in mounting the wick on the arms 30 and 31, the wick at one of the open ends is placed over the upper end of one of the arms 30 and 31 so as to cap the upper end of such arm for a substantial extent. The opposite open end of the wick sleeve is next related in like manner to the other arm 30 or 31, and then the intermediate portion of the wick is tucked down along the inner walls of the arms 30 and 31 to dispose the medial part 40M, Fig. 2, of the wick in contact with the medial part of the base member 21 between the arms 30 and 31. In other words, substantially the entire area of the arms 30 and 31 proceeding from the juncture line of the one web member 35 therewith across to the corresponding juncture line of the other web member 36 is lined with wicking material thereby establishing a relatively large wicking capacity for the lubricator.

As will be recognized from Fig. 1, the medial part of the base member 21 and the inner portions of the two outer sections 21A and 21B of the base member will, when the lubricator 20 is installed in operative position, be bathed in oil in the bottom of the journal box. This will likewise be true of the medial part 40M of the wick as well as the lower extents of the inner portions 40A and 40B of the wick that are suspended by the arms 30 and 31. It will therefore be recognized that the wick 40 is capable not only of soaking up a great quantity of oil because of the extensive area thereof, but is also capable of operating effectively so long as the supply of lubricant in the journal box is at least up to the medial part 40M of the wick.

It is important that a lubricator for the journal of a railroad car be secured within the journal box against displacement to assure that the lubricator is restricted to the journal portion of the car axle between the collar and the dust guard seat. This is easily accomplished in accordance with the present invention simply by affixing retainers to the outer or free ends of the two sections 21A and 21B of the base member 21. The retainers are adapted to complementally engage solid parts of the journal box, and such solid parts of the journal box are conveniently represented by the stop columns and the waste ledges described above.

Thus, and referring in particular to Figs. 1 and 6 of the drawings, retainer plates 50 and 51, of relatively rigid material such as fiber board or the like, are affixed in a suitable fashion to the free ends of the base member to project outwardly therefrom. Each of the retainer plates includes a flat base 52 which is disposed on what constitutes the upper side of the base plate 21 of the lubricator as viewed in Fig. 5, which is to say that the retainer plates 50 and 51 are on the side of the base 21 of the lubricator which is disposed toward the car journal when the lubricator is installed in its operative position. The retainer plates 50 and 51 are adapted to cooperate with the stop columns of the journal box, but inasmuch as a journal box may include both stop columns and waste ledges as described above, the retainer plates 50 and 51 just outwardly of the flat bases thereof are bowed convexly in the direction of the journal as shown in Fig. 1 so as to be capable of clearing the waste ledges WL-1 and WL-2.

The outermost extremities of the retainer plates 50 and 51 are so formed as to provide a pair of ears 55 and 56, Figs. 1 and 6, which are separated by relatively wide notches 57. The ears 55 and 56 are of sufficient length to extend upwardly along the front and rear walls of the

stop columns in the journal box with the notches 57 embracing the lower sides of the respective stop columns as shown in Fig. 1 of the drawing. Preferably, the ears 55 and 56 are of sufficient length as to have the free end portions thereof projected a substantial distance upwardly relative to the lugs L of the bearing B whereby the lugs of the bearing serve to limit movement of the retainer plates in the direction of the car journal J. It will be recognized that the ears of the retainers constitute abutments which are engageable with front and rear walls of the stop columns to limit displacement of the lubricator axially of the car journal. Likewise, the resultant shoulders 58, Figs. 1 and 6, formed in the retainers as a consequence of formation of the notches 57 constitute solid surfaces on the retainers engageable with the lower sides of the stop columns thereby limiting transverse displacement of the lubricator. It will be further realized that the spring nature of the arms 30 and 31 of the lubricator enables the journal J to be displaced vertically relative to the bearing B without damage or injury to or any adverse effect on the operativeness of the lubricator.

The lubricator described above is also preferably equipped with auxiliary retainers 60 and 61 fixed to the free ends of the base member 21 on the side thereof opposite the retainer plates 50 and 51. Thus, as shown in Fig. 1, the auxiliary retainer plates are so positioned as to be disposed beneath the waste retainer ledges, where provided in a journal box as FB, and hence constitute additional means, cooperating with the lower surfaces of the retainer ledges, to limit transverse displacement of the lubricator. It will be appreciated that any convenient and accessible solid projecting member within the journal box such as journal stops or the like, where provided, can also be utilized to cooperate with suitable complementally configured retainer plates.

Advantageously, and as shown in Figs. 1, 2 and 5, reinforce plates R of rigid material are molded in the medial portion 21M of the base member 21 between the lower edges of the arms 30 and 31.

A modified form of the invention is illustrated in Figs. 7, 8 and 9. In this instance, the lubricator 100 embodies but two essential parts, namely, a wicking cover 105 and a resilient base 106 having arms 107 and 108 molded integral therewith. Referring to Fig. 7, the base 105 has a length corresponding approximately to the length of the bottom wall of the journal box between the dust guard slot thereof and the base of the upwardly curved forward wall of the journal box as will be explained in more detail below, and as shown in Fig. 9 the width of the base 106 is such that the remote free side edges E thereof lie just below the journal box waste retainer ledges WL-1 and WL-2 whereby the latter tend to prevent any significant lateral shift of the lubricator in the journal box as shown in Fig. 9.

The arms 107 and 108 are of less length than the base of the lubricator as shown in Fig. 7 for a purpose to be explained and have free inner edges E1 that are spaced one from another to enable the opposite open ends of the wicking cover to be easily draped over full extents of the lubricator arms with the intermediate portion of the cover following the contour of the upper face of the base 106 in the journal box so as to be well submerged in the oil. The cover, if desired, can be fastened to the outer portions of the arms that merge into the outer extremes of the base. While different forms of fastening can be resorted to, we prefer to permanently secure brass grommets BG, Fig. 7, in such portions of the base, and removable fasteners F are passed through the cover and the openings in the grommets. In this way, the cover is anchored in place but can be readily removed and replaced when circumstances require.

The lubricator 100 embodies spring means that tend to urge the covered arms against the two lower quarters of the journal with a desired degree of pressure. Thus, a plurality of spring steel inserts 110 are molded in the

base 106 and the arms 107 and 108, each spring insert having an elongated arc portion embedded in the base of the lubricator and having end extensions embedded in the arms 107 and 108 as illustrated in Fig. 8.

5 While, as mentioned above, oil resistant hard rubber is advantageously employed as the resilient material for the lubricator base and spring-biased arms, other materials can be used such as molded fabrics, plastics and foams, felt or woven material. Figs. 10 and 11 illustrate another modification of the invention which for the most part is similar that shown in Figs. 7 and 8, and hence the essential differences only will be mentioned. Thus, the lubricator 200, Figs. 10 and 11, has the front and rear edges of the base thereof notched at a plurality of areas 15 210. Such notches or cut-outs provide aligned surfaces FS and RS respectively representing the front and rear edges of the base. The spaced surfaces that are in alignment afford a centering action assuring that the lubricator is not canted within the journal box. Thus, the rear surfaces RS are adapted to engage the bottom of the forward wall at the back of the journal box JB, Fig. 12, which affords in part the dust guard slot DS. Likewise, the base of the lubricator 200 is so dimensioned that the front surfaces FS will substantially abut the beginning 20 of the rising contour at the front of the journal box bottom wall. It should also be pointed out that this is the dimensioning of the lubricator 100 described above.

The arms 203 and 204 of the lubricator 200 are of shorter front to rear dimension than the base, and this is 30 particularly evident in Fig. 12. This same dimension is used for the arms 107 and 108 of the lubricator 100, and is selected so that the lubricator arms will be inboard of the collar C and fillet surface FLS of the journal J, Fig. 12, the fillet surface FLS being just forward of the dust guard seat DGS of the car journal. It should be pointed out that Fig. 12 is not a true representation of the operative condition in the journal box. Thus, under normal circumstances, the lubricator arm 204 would be folded under the journal in a spring-biased state in the manner illustrated in Fig. 9, but the arm 204 is shown in its 35 tensioned state in Fig. 12 to demonstrate clearly the dimensioning involved.

40 Openings 215 and 216 are located medially in the base of the lubricator 200, and these enable a hook tool to be applied thereto in removing or adjusting the lubricator. These openings, if found necessary, can be reinforced.

45 It will be seen from the foregoing that under the present invention there is afforded a lubricator for the journal of a railroad car axle of relatively uncomplicated and inexpensive construction. Thus, the lubricator of the present invention includes but a base member of flexible material capable of conforming to the bottom of the journal box at the interior thereof, a pair of integral arms flexibly secured at edges thereof to the base member, and a wick draped on and between the arms. The arms are under spring tension, and in operation the arms in effect clasp the journal holding the wick against opposed 50 portions of the journal, with the intermediate portion of the wick suspended from and between the arms of the lubricator dipping into the supply of oil within the journal box whereby oil is relayed by capillarity or wick action to the journal. If for some reason the wick becomes unduly worn or by chance somehow frayed, it is a simple matter to replace the wick. The manner in which the arms are flexibly secured to the base member 55 of the lubricator and spring urged toward one another enables the lubricator to accommodate, without undergoing any permanent set, relative downward movement of the journal in the journal box without damage to the lubricator. In fact, it is possible at this time for the lubricator to relay even greater quantities of oil to the journal.

60 It will moreover be recognized that the lubricator has neither a front nor rear side and hence it is immaterial which side is at the rear or front of the journal box. The 65

base of the lubricator has an extensive area and hence has good frictional contact with the bottom of the journal box from one side to the other and part way up the sides of the box which assures little movement of the lubricator due to the entailed friction over a wide area. By dimensioning the base and arms of the lubricator in the manner explained in connection with Fig. 12, the base is maintained against shifting axially parallel to the journal, and the wick is free of surfaces of the journal which might become fouled on the wick and which do not need to be lubricated in the first place.

Hence, while we have illustrated and described a preferred embodiment of our invention, it is to be understood that this is capable of variation and modification, and we therefore do not wish to be limited to the precise details set forth, but desire to avail ourselves of such changes and alterations as fall within the purview of the following claims.

We claim:

1. A lubricator for a journal disposed for rotation within a journal box and comprising, a base member in the form of a generally flat and rectangular sheet of flexible resilient hard rubber material, a pair of arms composed of said material molded integrally with said base member so as to be flexibly joined at their lower edges thereto and projecting in spaced divergent generally V-relation therefrom, a one-piece sleeve of wicking material woven in tube form and having the opposed open ends thereof capping the free end portions of said arms with opposed intermediate portions of said sleeve looped between and draped along the opposed inner faces of said arms and with the medial portion of said sleeve disposed closely adjacent the medial part of said base member between said arms, webs composed of said material integrally joined to said arms and said base member and serving as spring means for urging said arms toward one another upon spreading said arms apart, and retainers of relatively rigid material at the opposed inner ends of said base member.

2. A lubricator for a journal disposed for rotation within a journal box and comprising, a base member in the form of a generally flat and rectangular sheet of flexible resilient material, a pair of arms composed of said material molded integrally with said base member so as to be flexibly joined thereto and projecting in spaced relation therefrom, webs composed of said material integrally joined to said arms and said base member and serving as spring means for urging said arms toward one another upon spreading said arms, and wicking material having ends thereof removably related to the free end portions of said arms with opposed intermediate portions of said wicking material draped along the opposed inner faces of said arms and with the medial portion of said wicking material disposed closely adjacent the medial part of said base member between said arms, and retainers of relatively rigid material at the opposed inner ends of said base member.

3. A lubricator for a journal disposed for rotation within a journal box and comprising, a base member of flexible material adapted to be inserted in said journal box, a pair of arms of flexible material and flexibly secured to said base member so as to project therefrom in spaced relation, said base member of flexible material including a reinforcing member embedded in the portion of the base member between said arms, compressible spring means comprising a web of flexible material acting between said base member and each of said arms for urging said arms toward one another, and a one-piece

wick in tube form having open end portions supported on free ends of said arms and an intermediate portion suspended between said arms and disposed below the free ends of said arms substantially in contact with the portion of said base member between said arms.

5. A lubricator for a journal disposed for rotation within a journal box and comprising, a base member of flexible resilient material adapted to be inserted in said journal box, a pair of arms flexibly secured to said base member in spaced relation and projecting therefrom, spring means comprising a member integrally joined to an arm at a mid portion thereof and acting between said base member and each of said arms for urging said arms toward one another, and a one-piece wick in tube form having open end portions supported on free ends of said arms and an intermediate portion suspended between said arms.

15. A lubricator for a journal disposed for rotation within a journal box and comprising, a base member in the form of a generally flat and rectangular sheet of flexible resilient hard rubber material, a pair of arms integrally joined flexibly at their lower edges to said base member and projecting in spaced relation therefrom, said arms being joined to the base member at locations closely adjacent the opposed side edges of said base member, and a sleeve of wicking material having the opposed ends thereof capping the free end portions of said arms with opposed intermediate portions of said sleeve looped between and draped along the opposed inner faces of said arms and with the medial portion of said sleeve disposed closely adjacent the medial part of said base member between said arms.

25. A journal lubricator of the kind described disposed within the journal box of a railroad car between the bottom of the box and the bottom of the journal and comprising a base of flexible material having a lower face in complementary contact with the bottom of the box and part way up the sides, said base being continuous between the dust guard slot and the upwardly directed portion of the journal box at the front, a pair of arms of resilient material having ends molded integral with the upper face of the base and each being continuous from approximately the collar journal to the journal fillet surface just forward of the dust guard seat of the journal, said arms having free ends spaced from one another, spring means acting on said arms intermediate the free ends and the ends molded with the base for biasing said arms toward the journal, and wick means on said arms and dipping into oil in the bottom of the journal box and held against the lower part of the journal by said arms.

30. 6. A lubricator according to claim 6 wherein the front and rear edges of the lubricator have symmetrically arranged notches spaced inwardly from the side edges of said base for engaging journal box structure to prevent canting of the lubricator in the journal box.
